UNITED STATES PATENT OFFICE.

JAMES IRVING, JR., OF COLD BROOK, NEW YORK.

WIRE FASTENER FOR FENCEPOSTS.

Application filed July 7, 1922. Serial No. 573,333.

To all whom it may concern:

Be it known that I, JAMES IRVING, Jr., a citizen of the United States, residing at Cold Brook, in the county of Herkimer and State of New York, have invented new and useful Improvements in Wire Fasteners for Fenceposts, of which the following is a specification.

This invention relates to fasteners and 10 more particularly to a wire fastener for fence posts.

The primary object of the invention is the provision of a fastener adapted to be inserted in a mortise formed in a fence post, 15 the said fastener being of such construction as to securely fasten the wire to the post.

Another object of the invention is the provision of a fastener, so constructed as to 20 permit of its removal from a fence post, should it be necessary to repair the fence by substituting new wire for the old.

A further object of the invention is the provision of a fastener which is simple in 25 construction, the same being made of only two parts; easily and quickly assembled and cheap of manufacture.

With these and other objects in view, the invention resides in the novel construction, 30 combination and arrangement of parts, the essential features of which are hereinafter fully described, are particularly pointed out in the appended claims, and are illustrated in the accompanying drawing, in which:—

35 Figure 1, is a vertical sectional view through a fence post, showing a wire about to be fastened.

Figure 2, is a view similar to Figure 1, showing the device in clamping engagement 40 with the wire.

Figure 3, is a detail perspective view of one of the parts of the fastener.

Figure 4, is a view similar to Figure 3, of the other part.

45 Referring more particularly to the drawings the numeral 5 indicates my improved fastener, the same comprising two elements 6 and 7, shown in Figures 1 and 2, as applied to a fence post 8. The fence post is 50 mortised as at 9.

The element 6, of the fastener is stationary within the mortise 9, and is held therein by means of a lug 10, formed on one end of the element 6, said lug adapted to be sunk in a 55 recess 11, formed in the bottom wall of the mortise. A longitudinal groove 12, is pro-

vided in the enlarged end of the element 6 and inwardly of the groove 12, is a transverse recess 13, for the reception of the fastening wire 14.

The element 6 having been anchored in the mortise of the post, the element 7, is inserted, as shown in Figure 1. The element 7 has formed on its under side, a wedge 15, capable of reception in the groove 12, of 60 the element 6. The element 7, is slideable in the mortise 8, and at its inner end the same is provided with an enlarged head 16, having a wedge surface 17, said head adapted to ride or move over the surface 18 of the 65 element 6. When the element 7 is in a position as shown in Figure 1, the wedge 15 is free from the wire 14, but when the same is shown pushed into the mortise as shown in Figure 2, the wedge 15 is brought into binding 70 engagement with the wire 14 by means of the top wall of the mortise, thereby securely holding the same in position on the post. In order to compensate for the relative movements between the parts, the head 16 of the 75 element 7 is adapted to co-act with a wedge surface 19, on the element 6. A hole 20 is provided in the element 7 for the insertion of a tool, when it is desired to remove the fastener from the post.

80 While there has been shown and described what I consider to be the preferred form of my invention, I wish it to be understood that changes, alterations and modifications that come within the claims, may be resorted to 85 when so desired.

What I claim as new is:—

1. A wire fastener for fence posts having a mortise therein, said fastener comprising two elements, one of said elements adapted 90 to be held stationary within the mortise and having a longitudinal groove, a transverse recess inwardly of said groove for the reception of a wire, the other of said elements being provided on its under side with a wedge for co-action with the groove of the first mentioned element for clamping the wire in said recess.

2. A wire fastener for fence posts having a mortise therein, said fastener comprising two elements, one of said elements adapted 100 to be held stationary within the mortise and having a longitudinal groove, a transverse recess inwardly of said groove for the reception of a wire, the other of said elements being provided on its under side with a wedge for co-action with the groove of the 105 wire in said recess.

first mentioned element for clamping the wire in said recess, and means for compensating the relative movements between the elements.

5. In combination with a fence post having a mortise therein, a recess within said mortise, a wire fastener comprising two elements, one of said elements having a lug for reception in the recess of said mortise, a wire

receiving recess and a longitudinal groove; ¹⁰ the other of said elements constituting a wedge to co-act with the groove of said first element for clamping engagement with the wire.

In testimony whereof I have affixed my signature.

JAMES IRVING, JR.
